UNITED STATES PATENT OFFICE.

FREDERICK G. JAHN, OF NEW YORK, N. Y., ASSIGNOR TO THE INTERNATIONAL POSTAL SUPPLY COMPANY OF NEW YORK, OF NEW YORK, N. Y., A CORPORATION OF NEW YORK.

PRINTING MECHANISM.

1,065,945.

Specification of Letters Patent.

Patented July 1, 1913.

Application filed April 2, 1909. Serial No. 487,465.

To all whom it may concern:

Be it known that I, FREDERICK G. JAHN, a citizen of the United States, and a resident of the borough of Brooklyn, in the county of Kings and city and State of New York, have invented certain new and useful Improvements in Printing Mechanism, of which the following is a specification.

My invention, while relating to printing machines generally, has reference more particularly to that form of such machine which is employed to imprint formal indorsements or other matter upon bank checks or other articles, and in which the printing or impression mechanisms are brought into and held out of operation, when the machines are being actuated, by the respective presence and absence of the checks or other articles to be operated upon.

With machines of this character, it is essential that the constructing of the parts be such as to adapt the machine to imprint or otherwise operate upon checks or other articles that vary in length and in thickness, and to make this imprint or other impression at but a single place upon each, however long or short the checks or other articles operated upon may be. Moreover, with machines of this class, it is also essential that the imprint or impression be made upon each and every succeeding check or other article passed through them, and, that too, at the same relative position with respect to the forward ends of the checks or other articles, as may have been previously determined upon by the particular adjustments of the machine.

To accomplish the above-mentioned results, and to provide a machine of this general class, which, while greatly simplified and improved in various of its parts, shall, at the same time, be provided with means for positively actuating the element of the printing mechanism that is controlled in its movement by the presence and absence of the checks or other articles to be operated upon, and also with means for automatically feeding forward to the machine in successive order, from a mass supplied to it, the checks or other articles to be operated upon, are the objects of my invention. In the attainment of these ends, various forms of mechanism may be adopted. In order however to make possible a more thorough understanding of my invention, I have shown in the drawings

one specific embodiment thereof, which I will hereinafter first describe, and will then point out the novel features of the invention in the subjoined claims.

Referring to the accompanying drawings, which form a part of this specification, Figure 1, is a plan of a printing machine constructed in accordance with one form of my invention; Figs. 2, 3, and 4, side elevations thereof, taken from different view points and respectively looking in the directions of arrows 2*, 3*, and 4* in Fig. 1, with parts of the housings of the machine broken away in Fig. 4, and certain of the interior parts in that figure shown in section, and others in elevation; Fig. 5, a reverse plan view of the carrier detached, showing certain of the parts of the detector mechanism carried by it; Fig. 6, an edge view of the carrier, with portions broken away and with certain of the parts carried by it shown in section and others in elevation; Fig. 7, a horizontal sectional view taken in the line 7 7 of Fig. 4 and showing the carrier and its attached parts removed, with its cover or top plate broken away and certain of the parts below shown in elevation, and with one of the grippers illustrated in dotted lines in two positions; Fig. 8, is a horizontal fragmentary section taken in the line 8 8 of Fig. 9 and looking in the direction of the arrows 8* in this last mentioned figure, showing portions of the top plate or cover of the main housing of the machine, with a portion of the gear for operating the rotary printing or impression member of the printing mechanism and the devices by means of which this rotary printing or impression member may be brought into and held out of operation in one of their positions; Fig. 9, is a vertical sectional elevation of the parts shown in Fig. 8 looking in the direction of the arrow 9* in that figure; Fig. 10, a similar horizontal fragmentary view of the parts shown in Fig. 8, also taken in the line 8 8 of Fig. 9, with the portion of the top plate or cover of the casing omitted and the parts for bringing the rotary printing or impression member of the printing mechanism into and for holding it out of operation in a slightly different position; Fig. 11, a like horizontal section also taken in the line 8 8 of Fig. 9, with various of the parts for bringing the rotary printing or impression member of the printing mechanism into and

for holding it out of operation in a slightly different position, and with other of the parts coöperating with them and shown in Fig. 10, omitted; Fig. 12, a plan or face view of the gear wheel by which the rotation of the printing or impression member of the printing mechanism is effected, with certain parts carried by ¹, and the rotary printing or impression member illustrated in dotted lines in three different positions; Fig. 13, a vertical section of a portion of the machine taken axially through both the feeding disk and the intermediate gears through which it is rotated from the gear that rotates the rotary printing or impression member of the printing mechanism, which last mentioned gear is also shown in section, with the shafts by which the disk and the intermediate gears are supported illustrated in side elevation; Fig. 14, a vertical section of another portion of the machine taken in the line 14 14 of Fig. 7, and looking in the direction of the arrow 14* in that figure, certain of the parts being in side elevation; Fig. 15, a vertical section of a portion of the machine taken in the line 15 15 of Fig. 7 and looking in the direction of the arrow 15* in that figure; Fig. 16, a vertical sectional side elevation of certain of the parts employed for carrying and operating one of the grippers, detached, with the gripper blades broken away; Fig. 17, a side elevation of a fragment of the face of the carrier broken away, with one of the grippers in its operative position; Fig. 18, a horizontal section thereof, taken in the line 18 18 of Fig. 17, with the gripping blades omitted; Fig. 19, a sectional plan of the feeding and selecting devices detached; Fig. 20, a horizontal section taken on the line 20 20 of Fig. 6, looking in the direction of the arrow 20* in that figure, and Fig. 21, is a vertical section taken in the line 21 21 of Fig. 1.

In all the figures, like letters of reference are employed to designate corresponding parts.

A indicates the main housings in and upon which the various parts of the machine are mounted and carried, and B indicates the carrier by means of which the checks or other articles to be operated upon are successively selected and carried forward between the supporting and printing members of the printing mechanism to the point of their delivery.

In the construction of the main housings any approved form that will adapt it to perform its required functions may be adopted, and the same may be designed to either rest upon a bench or table, or be secured to a suitable stand prepared to receive it. As shown in the drawings however, these housings are constructed in a general rectangular form in horizontal section, with one of its sides provided with a circular portion ex-

tending outward therefrom and the whole composed of a base ¹, and of a cap or cover ², which is arranged at the required distance above the base and is connected therewith by a vertical casing ³ that extends between them, with its respective upper and under edges secured to or formed integrally with the outer edges of the cap or cover and the base, as shown. The carrier B, on the other hand, is constructed in the form of a disk or wheel, with its peripheral face ⁴ made of the proper width to suit it to its intended use, and is or may be secured upon the upper end of a shaft C, which is rotatively mounted in a suitable bearing ⁵ that is supported upon the cap or cover ² of the main housing A, either by being detachably secured to it by screws ⁶, or by being constructed integrally therewith as may be preferred. With the carrier B thus mounted, it is capable of rotation with its supporting shaft C, and, when in rotation, of coöperating with a separator or wiper D to successively select the checks or other articles to be operated upon, one at a time, from a mass or package supplied to it and carry them forward in that order to their place of discharge. To insure of its accomplishing these results, while yet preventing it from selecting more than a single check or other article at one and the same time, the periphery of this carrier is provided with a superimposed feeding surface ⁷, that is preferably formed from soft rubber or other adhesive material, which, in coming in contact with the surface of a check or other article, will adhere thereto and cause the check or other article to move forward with it by frictional adhesion, while the remainder of the mass or package is held from moving forward therewith, by the separator or wiper D, which, to accomplish that result, is preferably made from a flexible strip of rubber, or other adhesive material similar to that made use of in the formation of the feeding surface ⁷, and, extending inward across their forward ends, with its own inner end slightly overturned in the direction in which the carrier is rotated, presses with the inner side of its overturned end against the periphery of the carrier, as shown. As thus arranged, whenever the feeding surface ⁷ is moved forward with its carrier, it will, as is apparent, engage with the surface of the check or other article lying next to it and in the path of its movement, and carry it forward in its travel; while the separator or wiper D, extending inward across the ends of the other checks or articles composing the mass or package, and engaging with its overturned end portion the check or other article lying next to that selected by the feeding surface, will, not only prevent any of the others of the mass or package from moving forward, but,

in consequence of its adhesive action upon the check lying next to that selected by such feeding surface, will prevent that also from moving forward, and that too, without interfering with the movement of the one selected, and so on, each check or other article selected by the feeding surface in its forward movement being carried forward by it, while the others composing the mass or package are restrained from such movement. 5 While the carrier B is thus provided with the feeding surface b^1 to select and carry forward the successive checks or other articles to be operated upon, it is also equipped 10 with a supporting surface b^2 , which, in the preferred embodiment of my invention, is constructed of comparatively hard rubber, or other appropriate material that will present a smooth surface and be thereby incapable of removing a check or other article 15 from the mass or package supplied to the machine against the restraining frictional adhesive action of the separator or wiper, and yet present a sufficiently yielding bed 20 to the printing or impression surface during the printing operation to preserve the face of the type or other characters carried by it from injury. With the carrier B thus provided, the feeding and supporting surfaces 25 b^1 and b^2 will preferably be made of the same width as its periphery and of a combined length to extend entirely around the same. In being thus constructed of this longitudinal extension, when the feeding 30 and the supporting surfaces are combined, the feeding surface b^1 , in itself, is preferably constructed of a length that will occupy an arc of but a very few degrees on the periphery of the carrier, or of a length that is 35 only sufficient to afford a surface that will insure its engagement with, and its carrying forward of a check or other article each time that it passes the mass or package supplied to the machine; while the supporting 40 surface b^2 will be made of a length to substantially occupy the circumferential portions of its periphery not appropriated by the feeding surface, whereby the checks or other articles operated upon may be printed 45 or otherwise treated at practically any desired point along or throughout their length. As thus constructed and proportioned these surfaces may be secured to the periphery of the carrier in any ordinary or approved way. 50 I prefer however to secure them thereto by segmental strips b^3 and b^4 , which, constructed of metal or other appropriate material, with outwardly extending flanges b^5 on their opposite ends, are secured to the periphery 55 of the carrier between the approaching ends of the feeding and supporting surfaces, by screws b^6 , extending through the strips and engaging at their free ends with suitable threaded orifices formed in the periphery of 60 the carrier, with the outwardly extending flanges b^5 on their opposite ends overlying the respective ends of the feeding and supporting surfaces, as shown more particularly in Figs. 5, 17, and 18. 65 In some instances the feeding surface b^1 may be furrowed or otherwise roughened, as shown in Fig. 2, or the same may be left smooth, as shown in Figs. 17 and 18. I prefer however to furrow or roughen it, as a better hold upon the check or other article 70 is thereby attained, but either the roughened or smooth form may be adopted and the surface operate with efficiency. 75 As thus far described, only a single feeding and a single supporting surface has been referred to, and in practice the carrier B may be constructed of a diameter to accommodate only that number, in that case the selecting, carrying forward, printing, and delivering of but a single check or other 80 article at each rotation of the carrier will be effected. It is preferred however to construct the carrier of a diameter to accommodate a plurality of these associated feeding and supporting surfaces, whereby the 85 selecting, carrying forward, printing, and delivering of a plurality of successive individual checks or other articles during such rotation will be effected; and, in the form of the invention illustrated in the drawing, 90 it is shown as equipped with three of these associated feeding and supporting surfaces, but this is merely illustrative, and the carrier may be made of a diameter to adapt it to the accommodation of a greater or less 95 number of the associated surfaces, without in any way affecting the essentials of the invention. With the carrier B thus provided with the feeding and supporting surfaces b^1 and b^2 , the separator or wiper D is 100 so supported with respect to them as to have its overturned inner operative end normally pressed against them with a yielding pressure. To permit of the accomplishing of 105 this result, the separator or wiper is arranged within a suitable holder d , which is secured to the upturned end of a rod d^1 that extends backward therefrom to near the point of discharge of the checks or other articles operated on, and has its opposite 110 upturned end journaled in suitable bearings d^2 and d^3 , respectively formed in the overhung portion of the main housing A and in a bar d^4 , which is supported above it through the intervention of a stud d^5 and 115 a screw d^6 . As thus supported the separator or wiper is capable of a swinging movement 120 toward and away from the carrier; and in order to hold it forced forward against the feeding and supporting surfaces on the carrier by a yielding pressure, a spring d^7 is employed, which, while capable of various modifications and applications, is shown in the drawings as constructed in the form 125 of a plate spring with one of its ends se- 130

cured to the main housing A by screws d^{18} , and its opposite end bearing against the upturned portion of the rod d^1 that supports the holder d . While thus normally pressed against the carrier by a yielding pressure and capable of movement toward and away from it with its holder, the separator or wiper is also capable of longitudinal adjustment within the holder. In order therefore to allow for this adjustment, the holder d is provided with a seat or groove d^7 , which receives the separator or wiper, and along which it may be adjusted, as, when it becomes necessary to sever its over-turned end, because of its wear, and to replace it by a fresh portion, being held in any position to which it may be moved therein by a screw d^8 , which, threaded in a bar or lug d^9 , with which the holder is provided, engages at its free end therewith, as shown. As thus held and supported the separator or wiper extends inward toward the carrier with a slight incline in the direction in which the carrier is rotated and has its inner over-turned end similarly curved in the same direction. To provide however for varying the inclination of this separator or wiper with respect to the carrier, the bearing d^{10} , by which the holder d is secured upon the upturned end of the rod d^1 , is split in one of its sides, and is provided with a clamping screw d^{11} , whereby the bearing may be released from frictional engagement with the rod d^1 or be firmly clamped thereon. With the bearing d^{10} thus constructed the adjustment of the holder d around the upturned end of the rod d^1 , to bring the separator or wiper into any required inclination with respect to the carrier, may be effected by simply loosening the screw d^{11} , when the required inclined adjustment of the separator or wiper may be effected, after which the clamping of the bearing upon the rod and the holding of the parts in adjusted position may be accomplished by simply turning up the screw, as will be readily understood.

For supporting the checks or other articles to be operated upon and feeding them forward to the selecting devices, comprised in the carrier B and the separator or wiper D co-operating with it, various means may be employed. I prefer however to adopt for this purpose a disk E and a feeding roll E¹, which are arranged in rear of and in proper relationship to such selecting devices and are secured upon a vertical shaft E², that is rotatively mounted in a suitable bearing e formed in or carried by the main housing A, as shown more particularly in Figs. 1, 13, and 19. As thus arranged the checks or other articles X to be operated upon, are supplied in packages or in mass, and, standing up edgewise, are deposited upon the disk E, with one of their longitudinal edges

resting thereon, and the rear vertical surface of the package in contact with the feeding roll E¹. With the checks or other articles thus disposed they are held pressed against the feeding roll E¹ with a yielding pressure by a feed plate E³, and their feeding forward to the selecting devices is effected by simply rotating the vertical shaft E². To accomplish this rotation various expedients may be selected. I prefer however to effect it from the shaft C, and, to that end, I respectively provide that shaft and the shaft E² with gears F and e^1 , which are fixedly secured to them, and are operatively connected by intermediate gears e^2 and e^3 that are rotatively mounted upon a stud e^4 , with which the under side of the cap or cover of the main housing A is provided. The shaft E², being thus connected with the shaft C, and through it with the carrier B, the required feeding movements will be imparted to the disk E and feeding roll E¹, whenever the carrier is rotated; and in order to insure the efficient feeding action of these parts upon the checks or other articles being operated upon, I find it convenient to equip the feeding roll E¹ at or near its top and bottom ends with surfaces e^5 , which are preferably formed from comparatively soft rubber or other equivalent adhesive material, and to so construct the upper surface of the disk E that the checks or other articles carried forward by it rest thereon only throughout the forward portions of their length. To provide for the application of the rubber or other adhesive material to the top and bottom ends of the roll E¹ these ends are constructed with circumferential grooves e^6 , in which the material constituting the adhesive surfaces is arranged and secured; while to provide for the checks or other articles being fed forward resting upon the upper surface of the disk E throughout their forward portions only, this surface, instead of lying in a plane at right-angles to its axis, is cambered or formed slightly conical, whereby the checks or other articles in passing over and resting upon it in traveling to the point of delivery, will incline downward slightly, with their rear ends elevated, in which position they will be supported and guided by a supporting plate E⁴, disposed above and in close relationship to the upper surface of the disk, and fixedly held in that position by an upturned flange e^7 , which is secured to the bar d^4 by screws e^8 .

With the parts concerned in the supporting and feeding forward of the checks or other articles to the selecting devices constructed and organized as thus explained, the disk E and the feeding wheel E¹, in acting upon the checks or other articles being passed through the machine, will not only serve to carry them forward toward and against the rear of the holder d and the

separator or wiper D, but, in consequence of the upper surface of the disk upon which they rest rotating across their forward ends in the direction of the carrier B, it will cause these forward ends to move inward toward the point of contact of the separator or wiper therewith, and, at the same time, by its friction on their lower edges, destroy whatever adhesive action there may exist between them, with the result that the individual selection of the successive checks or other articles by the coöperative action of the carrier and the separator or wiper will be facilitated. While thus the feeding forward of the checks or other articles to be operated upon is automatically effected by the disk E and feeding roll E¹, the forward end of any folded or aberrant individual thereof is held in position and prevented from improperly passing inward toward the carrier B by a guide-plate e⁹, which, secured at its rear end to the upturned flange e⁷ of the plate E⁴ by screws e¹⁰, extends forward therefrom around the front of the feeding rolls E¹, in a circumferential groove e¹¹ formed therein, and terminates at its forward extremity at a point near the periphery of the carrier B, to which its forward end portion is substantially tangent. By these means, as will be seen, the proper holding of any crumpled or other distorted checks or other article in proper position to be engaged by the feeding surfaces b¹ of the carrier is insured.

In some instances the upper surface of the disk E may be provided with upwardly raised spots or protuberances, as shown, for instance, in an application for U. S. Letters Patent filed by me in the United States Patent Office September 21st, 1907, and serially numbered 393,981. In the present drawing however I have shown the surface of this disk as smooth, and either of these forms of disks may be employed as preferred, or as the nature of the work to be performed may require.

For supporting the feed plate E⁴, which acts against the checks or other articles operated upon to force them against the feeding roll E¹, any appropriate means that will accomplish that result may be adopted. The instrumentalities that I have found in practice to be the most efficient for the purpose consists of a rod e¹², which, journaled at its forward end in a bearing e¹³ secured to or formed on the back of the plate, extends outward therefrom, thence downward to a point below the overhung portion of the main housing A that supports the disk E, and thence backward thereunder to near the place of discharge of the checks or other articles, where, through its upturned rear end, it is journaled in bearings e¹⁴ and e¹⁵ respectively formed in such overhung portion and in the bar d¹, as shown in Figs. 1,

2, and 3. As thus supported this plate is capable of movement toward and away from the feeding roll E¹ through a considerable range of travel, whereby to permit of the supply of packages or masses of checks or other articles of different thicknesses to the feeding devices; and in order to provide for forcing it against the mass or package with a yielding pressure, whatever the thickness of the mass or package may be, I make use of a spring e¹⁶, which, while capable of various modifications, in the embodiment of the invention illustrated in the drawings is constructed of wire in spiral form that is coiled around the rear upturned end of the rod e¹², and, connected at one of its ends therewith, is at its other end, connected with the main housing A adjacent to the bearings e¹⁴, with which such housing is provided.

With the separator or wiper D coöperating with the feeding surfaces b¹ on the carrier B to successively select one after another the individual checks or other articles to be operated upon from the mass fed forward to them by the feeding devices E and E¹, the positive carrying forward of the checks or other articles thus selected to and between the printing and supporting members of the printing mechanism, and thence onward to the place of their discharge, is also effected by the coöperative action of such feeding surfaces with grippers H that are arranged in connection with them.

These grippers of which there will be a separate one employed in connection with each of the feeding surfaces, may be constructed in a variety of forms. In the specific embodiment of the invention selected for purposes of illustration however, each of these grippers is constructed in the form of an elongated loop, with two parallelly arranged curved spring sides h connected at their outer ends by a portion h¹, and is or may be formed from wire or other appropriate material bent into the required contour, as shown in Figs. 16 and 17. As thus constructed these grippers extend through the periphery of the carrier B in suitable orifices h² formed therein, and are free to be protruded and withdrawn through them as the clamping and releasing of their respective checks or other articles are required—see Figs. 5, 6, and 7. For supporting these grippers and imparting to them the necessary protruding and withdrawing movements I make use of a lever H¹ in connection with each, which, pivotally mounted upon the under side of the carrier whereby to move with it in its rotation, has fixedly secured at one of its ends the inner end of its respective gripper, and is vibrated back and forth on its pivot by appropriate means. The special means employed by me for this purpose consist of stationary cams

H² and H³, which are fixedly secured to the upper surface of the cap or cover a¹ of the main housings A, by screws h³ and, in this location, the levers H¹, in their travel with the carrier B, pass over them. As thus supported and carried, whenever any one of the levers H¹, in moving forward with the carrier, is vibrated in one direction, as, for instance, by the cam H², the gripper carried by it will be forced outward through the orifices, h², and, traveling outward through them in a curvilinear path eccentric to the periphery of such carrier, will force its outer free end against the outer surface of the check or other article selected and presented to it by the selecting devices, with the result that the check or other article will be firmly clamped against the coöperating feeding surface b¹ and held in that position until released therefrom. On the other hand, whenever the lever H¹ is vibrated in the opposite direction, as, for instance, by the cam H², then this gripper will be released from the check or other article with which it was engaged, and, traveling backward in an opposite direction, will be withdrawn wholly within the periphery of the carrier, with the exception of the part h¹ thereof that connects the outer ends of its curvilinear sides h, which part h¹, in order to lie flush with the peripheral surface of the carrier, will enter and rest within the groove h⁴ formed therein between the orifices h², as shown in Figs. 7 and 17.

With the clamping of the checks or other articles against the feeding surfaces b¹ and the releasing of them from the same thus effected by the gripper H, the end h⁵ of the cam H³ is so formed and related to the separator or wiper D that the grippers, in being forced outward by the former, will clamp the leading ends of the checks or other articles against the feeding surfaces at a point in close relationship to the latter; while the end h³¹ of the cam H² is so fashioned and positioned with respect to the place at which the checks or other articles are discharged that the grippers, in being forced inward by it, shall release their hold upon such checks or other articles at the point where their leading ends are to rest when the checks or other articles are delivered.

For securing the grippers H to their respective carrying levers H¹, various means may be employed. In my preferred form of construction however they are secured to the levers by a hub or boss h⁶, which, formed upon the upper surface of each at the appropriate point near one of its ends, is provided with a slot or kerf h⁷, formed axially across it in a direction longitudinally of the lever, for the reception of the overturned end of the gripper, which is arranged therein, and which is firmly clamped in that re-

lationship by screws h⁸ that pass loosely through the portion of the hub or boss on one side of the slot or kerf, and engage at their threaded ends with threaded orifices formed in the portion of the hub or boss on the opposite side thereof. By these means, as will be seen, not only are the grippers firmly secured to their respective carrying levers H¹, but provision is made thereby for adjusting and removing them when desired, as clearly appears in Figs. 5, 7, and 16. With the grippers H thus secured to the levers H¹, each of these levers is equipped near its middle point with an upwardly extending pivotal stud h⁹, and its pivoting to the under side of the carrier B is accomplished through the intervention of a bracket I and a bearing h¹⁰. Of these, the bracket I is fixedly secured to the under side of the carrier in radial relation thereto by screws i, while the bearing h¹⁰, with the pivotal stud h⁹ rotatively mounted therein, is immovably secured to it through the medium of an outwardly extending ear h¹¹, with which the exterior of the bearing is provided, co-operating with two similar ears h¹² formed on the side of the bracket, and between which the ear h¹¹ is firmly clamped by a screw h¹³, as shown in Figs. 5, 6, 16, and 20. As thus mounted, not only are the levers supported and caused to travel with the carrier, but they are also rendered capable of vibration in one or the other directions from the cams H² and H³; and in order to provide for their engagement with these cams as they travel over them, each of these levers H¹ is provided with a properly located stud h¹⁴ depending from its under side to the requisite distance to engage with them, and, to reduce the friction between the parts, is provided with a rotatable sleeve h¹⁵ that is held in place thereon by a screw h¹⁶, as clearly illustrated in the figures on the drawings last noted.

While the outward and inward movements of the grippers, to respectively clamp and release their hold upon the checks or other articles, are effected by the cams H² and H³, as the levers H¹ are carried over them in their travel with the carrier, these grippers are held at the extreme of their movements, after their carrying levers H¹ have traveled beyond those cams, by springs K, which are so disposed and operating as to hold them in both their outward and inward position. To accomplish this result, various forms and applications of springs may be adopted. I prefer however to employ for this purpose an extensible and contractible spiral spring applied under tension, and, to that end, I provide each of the levers H¹ with an arm h¹⁷, which, secured at one of its ends to the upper extremity of the pivotal stud h⁹, by a screw h¹⁸ or otherwise, extends back and therefrom in a direc-

tion away from the gripper, and is equipped at its opposite end end with an upwardly extending stud h^{10} , that has rotatively mounted upon it a friction sleeve h^{20} . As thus provided, one end of the spring K is connected with this friction sleeve h^{20} , and the other end thereof is connected with a pin k , which is secured to the under side of the carrier B in such relationship to the parts that when the lever H^1 is occupying an immediate middle position between its limits of vibration, this spring will exert its strain in a line passing directly across the axis of the stud h^9 , from one of its points of connection to the other. In being thus applied, the tension already possessed by the spring K will, as is obvious, be augmented by the vibratory movement of the lever H^1 from the time the lever starts to move, until, in its travel, the stud h^{10} carries the line of strain exerted by the spring over and beyond the axis of the pivotal stud h^9 , when the resilient quality of the spring will be brought into action and the cam then acting aided thereby in completing the vibratory movement of the lever, in whichever of the two ways it may be moved.

If the movement of the lever H^1 is in a direction to force its gripper outward into contact with the check or other article to be acted upon, then such check or other article, when the outer end of the gripper contacts with it, will serve as a stop to the further movement of the lever, and will in turn be not only tightly clamped between it and the feeding surface b^1 , but firmly held in that position by the spring until released therefrom by the action of the cam H^2 . On the other hand, if the movement of the lever H^1 is in a direction to withdraw its gripper, then, when this withdrawal is completed, the portion h^1 connecting the outer ends of the sides h of the latter will be brought back into contact with the bottom of the groove h^4 , which, serving as a stop, will prevent the further movement of the lever and gripper in that direction, and the two will then be held in the positions to which they are thus restrained by the spring K, until again carried forward in the opposite direction by the cam H^3 to protrude the gripper, and so on; the spring K thus serving to not only aid the cams H^2 and H^3 in effecting the last portion of the movement of the levers H^1 in one direction or the other, but also to hold the gripper either forced outward against the checks or other articles to clamp them against the feeding surfaces, or in their withdrawn position when not acted upon by such cams, as shown in Figs. 5, 6, 7, and 17.

For holding the checks or other articles to be operated upon against the carrier, as they are being carried forward from the feeding and selecting devices to and between

the printing mechanism, and thence to the place of their discharge, while, at the same time, providing for the carrying forward of any aberrant individual thereof that may not have been delivered from the mass in time to be engaged by the grippers, or that may have been drawn forward by its adhesion to some properly traveling check or other article, and causing its discharge from the machine before it reaches the printing mechanism, I make use of a roller L, which, preferably covered on its periphery with a band of comparatively soft rubber or other equivalent yielding material, or left plain, is arranged to bear against the periphery of the carrier, slightly in rear of the separator or wiper, and at an elevation thereon that will carry it wholly above the path of travel of the grippers, as they are moved outward to clamp the checks or other articles delivered to them by the feeding and selecting devices. With the roller thus arranged it may be rotated from the carrier through its frictional contact therewith, or otherwise. I prefer however to rotate it from the carrier through frictional contact, and, to that end, rotatively mount it upon the upper end of a stud l , which extends upward from the free outer end of an arm l^1 that is pivotally supported from the overhung portion of the cap or cover a^1 of the main housings A, by a screw l^2 . In being thus supported the roller, as will be seen, is capable of a swinging movement toward and away from the carrier; and in order to normally hold it pressed against the carrier with a yielding pressure, I make use of a spring l^3 , which, while capable of various modifications, is shown in the drawings as a plate spring, with one of its ends fixedly secured to the main housings by appropriate screws l^4 and its opposite end bearing against the stud l , as shown in Figs. 1 and 2. The roller L being thus pressed against the periphery of the carrier, it is obvious that any checks or other articles being properly carried forward by the feeding surfaces b^1 and the grippers H will be firmly pressed against the carrier by it; while any check or other article that may not have been delivered in time for engagement by the grippers will be carried forward by the action of this roller and the carrier upon it. Instead however of being carried between the members of the printing mechanism; the leading end of the check or other article thus carried, will not be held against the carrier after it passes the roller L, and, in consequence thereof, will have a tendency to pass off at a tangent to the carrier, with the result that, in following that course, it will be discharged from the machine before it reaches the printing mechanism.

With the successive presentation of the

individual checks or other articles to the printing mechanism accomplished by the instrumentalities above described, the printing or other operations performed upon them is effected by a printing or impression member M in coöperation with the supporting surfaces b^2 on the carrier B. In the construction of this printing or impression member M, various forms may be adopted, it only being essential that, whatever its character, it be capable of being brought into action to coöperate with the supporting surface or member to imprint or emboss the desired matter or object, or otherwise operate upon each of the checks or other articles passed between them, and then withdrawn therefrom to be again brought into action and coöperation with it when the second check or other article is presented, and so on. In the specific form of the invention which I have selected for the purpose of illustration however, it is constructed in the form of a cylinder, with a portion on one side of its axis cut away, and the surface of the portion remaining either provided with the legend or other matter or object to be imprinted or embossed upon the check or other article, formed upon or within it, or the same is so constructed as to receive appropriate type or blocks for performing that function. As thus constructed this printing or impression member M is secured to the upper end of a short vertically arranged shaft m , which is journaled in suitable bearings m^1 that are so located that, when, in its rotation, the surface of the cylindrical portion of the member is brought opposite to the supporting member b^2 on the carrier B, the printing, embossing, or other operation upon the checks or other articles will be performed thereby as they are carried forward between them. For supporting the printing or impression member in this relationship, while yet permitting of its yielding backward from the supporting member b^2 on the carrier B, to adapt itself to different thicknesses of checks or other articles operated upon by it, I preferably form the bearings m^1 in the free ends of arms m^2 , which extend outward from a hollow shaft or sleeve m^3 that is pivoted within the main housing A, in such a manner that the arms m^2 thereon shall extend outward from it in a vertical plane that is parallel to and outside of a line drawn tangent to the carrier B, as illustrated in Figs. 7 and 14. In pivoting this shaft or sleeve m^3 to the main housing A, various means may be employed. I prefer however to adopt for the purpose a stud m^4 , which, depending from an orifice formed in the cap or cover a^1 , is fixedly secured therein by a nut m^5 , and receives the shaft or sleeve which is rotatively mounted upon it, and which is held thereon by a screw m^6 , threaded in the lower end of the stud and coöper-

ating with an overlapping plate or washer m^7 , as shown. With the printing or impression member thus mounted, it is normally held pressed inward toward its coöperating supporting surface by spring pressure, whereby to be capable of yielding backward therefrom to accommodate itself to different thicknesses of checks or other articles passing between it and its coöperating supporting surface. To permit of this being accomplished, I make use of a spring m^8 , which is preferably, though not necessarily, constructed in coil or spiral form, and co-operates with a projection m^9 extending outward from the outer end of the arm m^2 . As thus employed, this spring bears at its other end against an abutment m^{10} , which is formed or otherwise secured to the inner side of the vertical walls a^2 of the main housing A, and at its inner end it bears against the outer side of the projection m^9 , being held at its outer end in proper position against its abutment m^{10} by a screw m^{11} , threaded radially through the vertical walls a^2 of the main housing A and entering its interior, while its inner end is similarly held in proper position against the outer end of its projection m^9 , by a nipple m^{12} , extending outward therefrom and likewise entering its interior. With the parts arranged as thus described the printing or impression member M is held pressed inward to its normal operative position by the action of the spring m^8 , but is yet rendered capable of yielding backward from that position against the stress of the spring, as the exigencies of its use may demand. While the printing or impression member is thus held pressed inward toward its coöperating supporting surface or member b^2 by the action of the spring, its movement in that direction is positively limited by a stop or abutment m^{13} , which, while capable of various modifications, is shown in the drawing as constructed in the form of a screw, which, threaded radially through the vertical walls a^2 of the main housing of the machine, and through an abutment m^{14} , with which those walls are provided on their inner side, bears at its free end against the outer side of a projection m^{15} that extends outward from the sleeve m^3 , as shown in Fig. 7. As thus arranged the inward swinging movement of the printing or impression member toward its coöperating supporting member, is not only positively limited, but provision is made through the screw or abutment m^{13} , for varying that limit.

With the printing or impression member M mounted as described, its rotation from the gear F on the shaft C is effected through the intermediary of a gear N, which is fixedly secured to the shaft m near its lower end. In order however to provide for the rotation of this member only when it is re-

quired to imprint, emboss, or otherwise operate upon a check or other article passing between it and its coöperating supporting surface n^2 , and for its quiescence at all other times, this gear N, instead of being provided with teeth n throughout its entire circumference, is equipped with them throughout only a portion thereof, with the teeth omitted from the portion of its periphery that corresponds to that of the periphery of the printing or impression member upon which its cut away portion is located, and is provided on this portion of its periphery with a segment n^1 , which serves as a stop, and which is formed on its outer face with an inwardly curved surface n^2 , corresponding in its curvature to that of the gear F, with the extremities of this segment terminating in tooth-like projections n^3 . As thus constructed, this segment, which is preferably made of a less thickness than the remainder of the gear, normally rests with its inwardly curved outer face in close relationship to the outer surface of the teeth of the gear F, and, by contacting with that surface, prevents the rotation of the printing or impression member M, when it is to be held from rotation, but permits of that movement when its rotation is required. To provide for this rotation at the required times, the gear F is equipped at the proper points in the upper portion of its periphery with recesses n^4 , which are constructed of such form and size that they allow of the extremities n^3 of the segment n^1 entering them when the appropriate recesses and extremities are brought opposite to one another, with the consequent rotation of the gear N by the engagement of its teeth n with the teeth on the periphery of the gear F, as shown more particularly in Figs. 8, 10, 11, and 12. With the extremities n^3 of the segment n^1 thus co-operating with the recesses n^4 when the printing or impression member is being rotated, its inwardly curved surface n^2 will, when that rotation is being completed, swing inward over the surface of the teeth of the gear F, and thereby arrest the further movement of such member, holding it in a state of quiescence until its rotation is again required, when the proper recesses n^4 in the gear F will be brought into position beneath the gear N and a second rotation of the same effected, and so on.

For bringing the teeth n on the gear N into engagement with the teeth on the gear F, when the rotation of the printing or impression member is to be effected, various means may be adopted. I prefer however to employ for this purpose an arm n^5 , and a co-operating abutment n^6 . Of these, the arm n^5 is fixedly secured upon the shaft m , and, extending outwardly from it, has its rear operating surface so formed that it is curved outwardly and rearwardly, as shown; while

the abutment n^6 is preferably constructed in the form of a lever, with its forward operating end n^7 preferably enlarged and made circular in form, and its rear end bifurcated, whereby to form two rearwardly extending portions n^8 and n^9 . As thus constructed this abutment is preferably pivoted at the proper point upon the upper surface of the gear F, by a pivot n^{10} , whereby to permit of its forward end n^7 being swung outward to engage with the rearwardly curved surface of the arm n^5 , with its center in approximate coincidence with the pitch-line of the gear F, as shown in Figs. 10 and 11, or of being swung inward therefrom to a position that will allow of its passing the outer end of such projecting arm without engaging therewith, as shown in Fig. 8. In being thus operated the rotation or quiescence of the printing or impression member M, when the gear F is being rotated, is determined by the position in which the abutment is adjusted. When swung outward to its outermost position it will engage with the outwardly and rearwardly curved surface of the arm n^5 , and, carrying this arm along with it around its axis, will cause the rotation of the printing or impression member thereby. On the other hand, when adjusted to its innermost position then it will pass beyond the outer end of the arm n^5 without engaging with it, in which case the printing or impression member will remain in quiescence. While the printing or impression member may thus be brought into or left out of operation by simply moving the appropriate abutment to its respective outer or inward position, the engagement of the teeth n on the gear N with the teeth of the gear F is positively and gradually accomplished by so relating the outwardly and rearwardly extending curved surface of the arm n^5 to the first tooth of the series of teeth on the gear N, and to the forward end of the abutment, that, in operating to carry the arm n^5 around its axis, the forward end of the abutment will engage with this curved surface at its rear outer end, as shown in Fig. 10. In being thus engaged therewith, and moving forward in its course, the curved surface will travel down along the same, until the forward end of the abutment reaches a point in its travel that will be coincident with the pitch-line of the teeth on the gear N, as shown in Fig. 11, when the first tooth of the series on that gear will be brought opposite to the space between the appropriate teeth on the gear F and its proper engagement therewith effected. The engagement of the teeth n on the gear N with the teeth on the gear F, being thus effected through the co-operation of the abutments n^6 with the outwardly and rearwardly curved surface on the arm n^5 , the swinging movement of each of these abutments upon its pivot, is limited

by a stop-pin n^1 , which is preferably secured in the upper surface of the gear F at a point between the rearwardly extending portions n^8 and n^9 thereof, and contact with 5 one or the other of those portions, as the abutment is swung to one or the other of its adjusted positions, with the result that its movement is limited thereby. With the abutment n^6 constructed and operating as 10 thus explained, a separate one will be employed in connection with each of the associated grippers H and feeding surface b^2 , and the same will be so located with respect to those parts on the gear F, that, when 15 each of these associated grippers and feeding surfaces approaches the position where the required imprint or other operation is to be performed by the printing mechanism upon the check or other articles gripped between them, the forward end of this abutment n^6 , will, in its travel with the gear F, be brought into contact with the rearwardly curved surface of the arm n^5 , carrying it 20 forward around its turning axis, with the result that the printing or impression member will be brought into action and the proper imprint or other operation performed upon the check or other article at the exact location thereon required. While 25 the rotation of the printing or impression member M is thus caused by the abutment n^6 , when the latter is in proper adjustment, and the arrest of its rotation accomplished by the co-operation of the curved surface n^2 30 of the segment n^1 with the outer surface of the gear F, I prefer to supplement these arresting means by stops n^{12} , against which the outer end of the arm n^5 abuts at the instant the rotation of that member is completed. 35 These stops, which are preferably constructed in the form of bars, with their outer edges curved to a radius slightly less than that of the gear F, are secured to the upper surface of such gear opposite the 40 places where the outer end of the arm n^5 rests at the completion of the different rotations of the printing or impression member, by screws n^{12} , as shown in Fig. 12. As thus supported, these stops, in being carried around with the gear F, will be separately brought opposite the end of the arm n^5 , as the successive rotations of the printing and impression member are completed, and afford, by the contact of each therewith, 45 a stop to its further movement, with the result that the jar or strain that would be occasioned to the parts by the violent carrying of the curved surface n^2 of the segment n^1 against the outer surface of the teeth on the gear F will be thereby obviated.

To accomplish the outward and inward swinging movement of the abutments n^6 , to respectively carry them into and out of engagement with the arm n^5 , as they are carried forward by the gear F, various ar-

rangements of mechanism may be adopted. I prefer however to employ for this purpose a switch O, which, pivoted to the under side of the cap or cover a^1 of the main housings A, in a plane above the abutments, by 50 a pivot o , extends outwardly from such pivot in a direction opposite to that in which the abutments are carried, and is constructed with the opposite edges of its free end portion inclined inward toward 55 each other until they meet at a point or edge at its outer extremity. In being thus constructed and supported, this switch is capable of an outward and inward swinging movement on its pivot over the path of 60 travel of the abutments n^6 , and of engagement with the forward operating ends of such abutments as they are carried under it, being limited in its respective outward and inward movements by stop-pins o^1 and 65 o^2 , which, fixedly secured in the under side of the cap or cover a^1 of the main housings, extend downward therefrom to the proper distance to perform that duty. For permitting of the engagement of this switch O 70 with the abutments n^6 , I provide the forward end n^7 of each of the latter with a pin o^3 , which, fixedly secured at its lower end therein, extends upwardly from its upper surface to the proper distance to engage 75 with one or the other of the edges of the switch when brought opposite to it; and in order to provide for its engagement with them only throughout the free end portion 80 of the switch, while yet permitting of its passing under the remaining portion of the latter, this switch is so constructed that its free end portion lies in a somewhat lower plane than does the remaining portion of it, as shown more fully in Figs. 7, 8, and 10. 85 With the switch constructed and arranged as thus explained, whenever it is swung inward to the limit of its inward movement against its stop-pin o^2 , then the successive abutments in traveling forward with the 90 gear F, will engage through the respective pins o^3 in their forward ends n^7 , with its outward inclined edge, and, through such engagement, be deflected outward to the outer limits of their movement, in which position their forward ends will engage with the 95 outwardly and rearwardly curved surface of the arm n^5 , causing thereby the rotation of the printing or impression member M as before explained. On the other hand, whenever the switch is swung outward to the 100 outer limit of its movement, into contact with the stop-pin o^1 , then the successive abutments n^6 as they travel forward with the gear F, will engage at their forward 105 ends, through their respective pins o^3 , with its inward inclined edge, and through such engagement will be deflected inward to the inner limit of their movements, in which position they will pass the outer end of the 110

arms n^5 without engaging with it. Thus through the switch O the outward and inward swinging movement of the abutments to render them operative or inoperative may be effected, as the switch is swung outward or inward on its pivot in the required direction. For thus swinging the switch O in the proper direction to cause it to place the abutments in their operative or inoperative position, as their presence in one or the other is required, various means may be employed. I prefer however to adopt for the purpose a detector P in connection with each of the associated grippers and feeding surfaces, and to so connect it with the switch O, that when the proper delivery of the check or other article upon the surface of the carrier has been effected by the appropriate feeding surface and the separator or wiper D, the switch will be swung to the inner limit of its movement, and that when such delivery has not been made by them it will be swung to the outer limit thereof. With the detectors thus employed they are preferably constructed in the form of rods, which, fitted to slide radially of the carrier B in suitable bearings p secured to its under side, are adapted to work at their outer ends through the periphery of the same in suitable bearings p^1 formed or otherwise secured in it, and are provided with downwardly turned rear end portions p^2 . As thus constructed these detectors coöperate with a curved guide wall p^3 and with a curved arm p^4 , of which the former extends upwardly from the cap or cover a^1 of the main housings A in concentric relationship to the shaft C, while the latter, which is curved to a somewhat greater radius, is disposed outside of the guide wall p^3 , and is secured at the end thereof with which the downturned ends of the detectors first contact, to the upper end of a short vertical shaft p^5 that extends downward through, and is rotatively mounted in, a bearing p^6 , formed in the cap or cover a^1 , with a second arm p^7 fixedly secured at one of its ends to the lower end of such shaft and having its other end connected with the switch O by a rod p^8 , which, extending between them, is jointed at one of its ends to the switch and at its other end to the arm p^7 . With the parts thus arranged and organized, each of the detectors is normally pressed outward by a spring p^9 , which, coiled around it, bears at one of its ends against the inner bearing p , and at its outer end against a collar or abutment p^{10} , which, fixedly secured to its respective detector by a screw p^{11} , also serves as a stop to limit the outward movement of the same; while the outer free portion of the curved arm p^4 is normally held in contact with the guide wall p^3 , by a spring p^{12} , which, connected at one of its ends with the outer end of the arm p^7 , is secured at its

other end to a cap or cover a^1 , as shown in Fig. 10. In being thus arranged, whenever a check or other article is delivered by any one of the feeding surfaces b^1 and the separator or wiper, the respective detector answering to that feeding surface will be held by the presence of the check or other article from protruding beyond the periphery of the carrier, and its down-turned inner end portion p^2 will be thereby compelled, in its movement with the carrier, to travel around on the inner side of the curved guide wall p^3 , with the result that the switch O will be held in its inner limit of motion, and the abutments thereby carried outward into position to engage with the arm n^5 of the shaft m , with the consequent rotation of the printing or impression member M. On the other hand, when the feeding surface and the separator or wiper fail to deliver the check or other article at the desired time, then the detector answering to that particular feeding surface will be protruded to the outer limit of its movement, and its down-turned rear end portion p^2 thereby caused to travel around on the outside of the guide wall p^3 , and between it and the inner surface of the curved arm p^4 , with the result that, not only will the free end of this arm p^4 be carried outward into the position shown in Figs. 7 and 8, but the switch O swung outward to its outer limit of movement, and the abutments, through its action upon them, carried inward to such position as to pass the arm n^5 without engaging with it. While the inward and outward swinging movements of the switch O are thus accomplished by the coöperation of the downturned end portions p^2 of the detectors with the curved guide wall p^3 , the curved arm p^4 , and the spring p^{12} , the detachment of the checks or other articles from the surface of the carrier, when they reach the place of their discharge and are released from the hold of their respective grippers and feeding surfaces, is also accomplished by these downturned end portions p^2 , through their respective detectors, and other appropriate means. To this end I make use of two disconnected stationary cams p^{13} and p^{14} , which, extending upwardly from the cap or cover a^1 of the main housings A, on the side of the shaft C opposite to that occupied by the curved guide wall p^3 , are separately constructed with a curvilinear portion 1 of substantially the same radius as that of the guide wall p^3 , and are arranged with these curvilinear portions in concentric relationship to said shaft C, with the curvilinear portion of the cam p^{13} provided at its end with an outwardly curved portion 2, extending rearwardly therefrom across the path of travel of the down-turned end portions p^2 of the detectors, and in a direction opposite to that in which these

down-turned end portions travel with the carrier B; while the curvilinear portion 1 of the cam p^{14} is constructed at one of its ends with an outwardly curved portion 3, which 5 extends rearwardly beyond the curvilinear portion 1 of the cam p^{13} , and at its other end with a similar outwardly extending portion 4 that nearly reaches the pivoted end of the curved arm p^4 , as shown more particularly in Figs. 7, 8, and 10.

With the wall p^3 , the cams p^{13} and p^{14} , and the curved arm p^4 , constructed and arranged as above explained, the successive detectors as they arrive opposite the point 15 where the checks or other articles are being delivered, will, as their respective feeding surfaces and grippers engage and grip the individual checks or other articles presented to them, be permitted, through their down- turned rear end portions p^2 entering the outwardly curved portion 4 of the cam p^{14} , to move outward if unstrained. If however their respective feeding surfaces and grippers engage with and grip the checks or 20 other articles presented to them, then the detectors will not be permitted to move outward through the periphery of the carrier, by their contact with them, but will be held in such position that their down-turned 25 inner ends p^2 will engage with the inner side of the guide wall p^3 , and, in their movement with the carrier B, will travel around in contact with it, while the checks or other articles will be carried forward between the members of the printing mechanism and the proper imprint or other operation performed upon them. If, on the other hand, their respective coöperating grippers and feeding surface fail to engage and grip 35 the checks or other articles presented to them, then the detectors, in arriving at the point where their down-turned ends enter the outwardly extending curved portion 4 of the cam p^{14} , will, by the action of their respective springs p^9 , be forced outward through the periphery of the carrier, and their down-turned ends, in their forward movement, will enter between the outer surface of the guide wall p^3 and the inner 40 surface of the curved arm p^4 , traveling around between them, with the result that the printing or impression member M will not be brought into operation as the detectors pass it. In thus moving forward with the carrier B, the down-turned ends of the detectors will travel forward along the inner or outer surface of the guide wall p^3 , as their respective coöperating grippers and feeding surfaces engaged or failed to 45 engage with the respective checks or other articles presented to them, until they approach the place for the discharge of the checks or other articles, when they will then pass beyond the wall p^3 , and such of them 50 as may have traveled around the outer sur-

face thereof will be engaged by the inner surface of the outwardly curved portion 2 of the cam p^{13} , where the detectors, through such engagement, will be withdrawn to their inner limit of movement. 70 Having been thus withdrawn they will, in their further movement with the carrier, be held, with those already in that position, until they arrive at the end of the curvilinear portion 1 of the cam p^{13} , when they 75 will be protruded immediately after their respective grippers release their hold upon such checks or other articles, to detach the latter from the surface of the carrier to which they may be adhesively held by electricity or otherwise. With the detectors thus protruded, their down-turned ends, in their further travel with the carrier, will engage with the outwardly curved portion 3 of the cam p^{14} , when their respective detectors 80 will be withdrawn to their inner limit of movement and there held until their down-turned portions enter the outwardly curved portion 4 of that cam, when they will be free to move outward to protrude 85 their outer ends through the periphery of the carrier, unless prevented by the checks or other articles presented to and gripped by their respective grippers, and so on. In order therefore to provide for the detectors 90 acting upon the checks or other articles delivered to their respective coöperating grippers and feeding surface in close relationship to the separator or wiper, the outwardly curved portion of the cam p^{14} , and the bearings p^1 for the detectors in the periphery of the carrier, are so located with respect to their coöperating grippers and feeding surfaces that the detectors, when the grippers are moved outward to the limit of 95 their outer movement and are clamping their respective checks or other articles between them and their coöperating feeding surfaces, will either contact with such check or other articles at points slightly in rear of the 100 outer ends of those grippers, or of the part h^1 , which connects the outer ends of the curved spring sides h , or be protruded at that point, if no checks or other articles be gripped by them. 105

With the successive checks or other articles selected one at a time by the coöperating of the feeding surfaces b^1 and the separator or wiper D from a mass supplied to them by the feeding devices, and carried forward in that order between the printing and supporting members of the printing mechanism, to receive the appropriate imprint or other operation that is to be performed upon them, their discharge may be 110 effected at any location in the subsequent course of their travel that may be desired. I prefer however to locate this place of discharge immediately in rear of the guide- plate e^6 , and to provide for arranging the 115 120 125 130

checks or other articles as they successively arrive at that place the one against the other in packages. To this end, I make use of a plate S for supporting the checks or other articles as they are successively delivered, and so fashion and locate the rear portion h^5 of the cam H^2 , that, upon the succeeding checks or other articles arriving at a point slightly in rear of that at which their forward ends are to rest, their respective grippers will be released from them, allowing such checks or other articles to move forward slightly thereafter to the exact position they are to occupy when delivered.

To permit of the plate S serving as a support for the checks or other articles as they are delivered, this plate preferably stands upright on one of its edges, and is capable of movement toward and away from the carrier B on slides s formed on the upper surface of the cap or cover a^1 of the main housings of the machine, being held in its upright position by a rod or bar s^1 , which, fitted to slide in suitable bearings s^2 secured to the under surface of the cap or cover a^1 , has its outer end s^3 bent upward vertically and receives the plate S, which is fixedly secured to its inner face by rivets or other appropriate means. In its inward position this plate S will lie in close relationship to the periphery of the carrier B, but will be gradually moved outward therefrom by the succeeding checks or other articles as they arrive opposite it; and, in order to provide for its occupying its inward position, the cap or cover a^1 of the main housing is provided with a slot s^4 for the accommodation of the up-turned end s^3 of the bar or rod s^1 as it moves back and forth with the plate S. With the succeeding checks or other articles thus delivered against the plate S, their forward movement after such delivery is prevented by a stop T, which, preferably constructed in plate form and standing up vertically on one of its edges, is hinged at its outer end upon the stud d^5 , and extends inward across the leading ends of the checks or other articles, with its inner end bent rearwardly slightly and provided with a projecting portion t at its upper edge which extends inward over the carrier in approximately radial relation thereto, as shown in Figs. 1, 3, and 4. In being thus arranged this stop T will preferably be held in the position shown in Fig. 3 by a light spring t^1 , which, secured at one of its ends to the upper surface of the cap or cover a^1 , by screws t^2 or otherwise, engages at its outer end with the lower edge of such stop and prevents any forward movement of the checks or other articles after they have been released from their respective grippers and properly delivered. In order however to provide for this stop yielding, in case of a

torn check or other article becoming engaged with the carrier or with the parts carried by it and carried forward thereby against the stop, the engagement of the spring t^1 with the lower edge of the same is through a shallow notch formed in its free end, which, while sufficient to resist the ordinary pressure against the stop will yet yield thereto when the pressure exceeds a certain limit.

With the parts arranged and operating as above explained, the checks or other articles operated upon will be delivered in successive order between the carrier and the supporting plate S; and in order to provide for the detachment of such checks or other articles from the periphery of the carrier B, to which they may adhere by the action of electricity or otherwise, the end of the curvilinear portion 1 of the cam p^{13} is so related to the stop T and to the rear end portion h^5 of the cam H^2 , that immediately after the successive grippers release their hold upon the checks or other articles carried by them, the coöperating detectors will be rapidly protruded through the periphery of the carrier against them and then withdrawn, as before explained, with the result that the detachment of such checks or other articles therefrom will be effected. In thus carrying forward the checks or other articles from the point of their presentation to the grippers, to the place of their discharge, no pushing action is exerted upon them whatever. On the contrary, the engagement of the grippers with them to clamp the checks or other articles to their respective feeding surfaces b^1 , is at their forward ends, and in being carried forward from the point where they are first engaged and clamped, to their place of discharge, they are drawn or pulled along behind the devices that clamp them to the carrier. This is a result that is extremely advantageous, for, while letters and other stiff articles may be pushed forward through the machine, a more efficient carrying forward of checks and other light pliable articles is accomplished when they are drawn or pulled forward in their course by power applied at their leading ends, as will be readily understood.

With a view to adapting the machine to the printing or the performance of their required operation at any predetermined point on the check or other article transported by the carrier, the carrier, with the parts supported by it, is so mounted as to be capable of a circumferential adjustment forward or backward with respect to the printing or impression member M. To this end, the carrier B, instead of being fixedly secured to the shaft C, which carries the gear F, is secured thereto through the intervention of clamping members c and c^1 , between which it is clamped. Of these, the member

c is fixedly secured to the shaft *C* by a pin *c*² or otherwise, and is provided on its periphery with a circumferentially arranged rabbet *c*³, which receives the hub *c*⁴ formed around the axis of the carrier, with the member *c*¹ overlapping the upper surface of such hub and firmly clamped to the member *c* by screws *c*⁵, passing through the former and engaging with the latter. As thus arranged, the securing of the carrier *B* to the shaft *C* is effected through the clamping action of these members *c* and *c*¹ alone. With the carrier thus secured in place its circumferential adjustment with reference to the printing or impression member *M* will be effected by simply loosening the screws *c*⁶, and turning the carrier around the member *c* in the rabbet *c*³, to the required distance to locate the imprint or other impression that is to be made upon the check or other article, when it may be firmly clamped in its adjusted position by simply tightening up the screws; and in order to indicate the extent of the movement of the carrier in making the required adjustment, the carrier is conveniently provided with a pin *c*⁸, which, extending upward from it, works in a circular recess *c*⁷ formed in the periphery of the member *c*¹, as shown in Figs. 1 and 4.

While, in the form of machine shown and described, the rotation of the various parts are in horizontal planes on vertically arranged axes, and the widthwise dimension of the printing or impression and the supporting members are such as to render the machine especially applicable to the printing of formal endorsements or other matter on the back of checks or other similar articles, it is to be understood that the parts may be arranged to rotate in vertical planes on horizontally arranged axes, and the widthwise dimension of the printing or impression and the supporting members be made such as to adapt the machine to print or otherwise operate on other surfaces or articles, without in any way changing the essential characteristics of the machine.

From the foregoing it will therefore be seen that I produce a printing mechanism, which, while capable of wide and varied application, is yet simple in construction, automatic and positive in its action, and capable of rapid operation when in use.

With the machine constructed and organized as above explained, the rotation of the carrier *B* may be effected from any convenient motor or by the hand of the operator. In the drawings however, I have shown this rotation as effected by hand, and, to that end, I have illustrated it as provided with a suitable handle *V*, through which that result may be accomplished. Again: For supplying ink to the printing or impression member *M*, any ordinary or well known

forms of mechanism may be employed. I have however shown it applied thereto through an inking roll *W*, to which the ink may be supplied in any convenient manner, and from which it may be transferred to the surface of the printing member in the customary way.

Although in the preceding I have described the best means contemplated by me for carrying my invention into practice, I wish it distinctly understood that I do not limit myself thereto, as it is obvious that the same may be modified in various of its parts without departing from the spirit of the invention.

Having now described my invention and specified the best means contemplated by me for carrying it into practice, I claim and desire to secure by Letters Patent of the United States,

1. The combination, with a rotary carrier provided with a feeding surface, and a separator or wiper coöperating with it, of a conical or cambered rotating disk and a rotating feeding roll for respectively supporting and carrying forward checks or other articles to be operated upon to said carrier and separator or wiper, and a movable plate for operating against such checks or other articles with a yielding pressure to force them against the feeding roll, whereby said checks or other articles supplied in mass will be automatically fed forward to the action of the carrier and the separator or wiper, and their forward ends, not only carried inward toward the carrier, but separated from one another, substantially as described.

2. The combination, with a rotary carrier provided with a feeding surface, a separator or wiper coöperating with it, and a rotating disk and a rotating feeding roll for respectively supporting and carrying forward checks or other articles to be operated upon to said carrier and separator or wiper, of a guide-plate fixedly secured in place and extending inwardly around the feeding roll to a point near the periphery of the carrier, and a movable feed plate for operating against such checks or other articles with a yielding pressure to force them against the feeding roll and toward the guide-plate, whereby said checks or other articles supplied in mass may be automatically fed forward to the action of the carrier and the separator or wiper, and the deflection of any folded or aberrant individual thereof prevented from improperly moving inward toward such carrier, substantially as described.

3. The combination, with a rotating feeding roll provided with a yielding surface at its top and bottom ends, and a feed plate, of a supporting rod jointed at one of its ends to the feed plate and journaled at its

ether end in the main housing of the machine, and a spring for coöperating with such supporting rod, whereby such feed plate is rendered capable of an outwardly swinging movement and is forced inward toward the feed roll by a yielding pressure, substantially as described.

4. The combination, with a rotating feeding roll, a feed plate coöperating therewith, the main housings of the machine, and a stationary bar arranged above and fixedly supported therefrom, of a supporting rod jointed at one of its ends to the feed plate and pivotally supported at its opposite ends in bearings formed in said main housings and stationary bar, and a spring secured at one of its ends to such supporting rod and at its other end to the main housings, whereby the feed plate is supported and, not only rendered capable of a swinging movement with said supporting rod, but forced inward toward the feed roll by a yielding pressure, substantially as described.

5. The combination, with a rotating feed roll provided with yielding surfaces at its top and bottom ends, the main housings of the machine, and a supporting plate fixedly secured to such main housings, of a guide-plate fixedly secured at one of its ends to such supporting plate and extending inwardly around the feeding roll between its yielding end surfaces to a point in close relationship to the periphery of the carrier and substantially tangential thereto, substantially as described.

6. The combination, with a holder constructed with a seat or channel adapted to receive a yielding and flexible strip and permit of its adjustment along the same, a swinging rod upon which it is supported, and means whereby the holder may be rendered capable of a rotary adjustment around an axis that is at right-angles to its swinging supporting arm, substantially as described.

7. The combination, with a separator or wiper constructed of a soft yielding material, and a carrier provided with a feeding surface for coöperation with the separator or wiper, of a supporting rod pivoted at one of its ends to the main housings of the machine and provided at its other end with an upturned end, and a holder provided with a seat or channel for reception of the separator or wiper and along which it may be adjusted toward and from the carrier and also with a compressible bearing for engagement with the upturned end of the supporting rod, whereby the separator or wiper may be, not only swung toward and away from the carrier, and be adjusted toward and away from the same in its holder, but also adjusted around the upturned end of its supporting rod to vary its inclination with

respect to the path of movement of the carrier, substantially as described.

8. The combination, with a holder constructed with a seat or channel adapted to receive a strip of soft yielding material, and means by which the holder may be supported and rendered capable of adjustment around a vertical axis, of a strip of soft yielding material arranged in such seat or channel, and devices by which such strip may be fixedly held in any position to which it may be adjusted in said seat or channel, substantially as described.

9. The combination, with a rotating carrier provided with feeding surfaces of soft yielding material, a separator or wiper also constructed of a soft yielding material for coöperating with the carrier, and a holder in which such separator or wiper is supported with its inner end overturned in the direction in which the carrier is rotated, of a supporting rod jointed at one of its ends to the main housings of the machine and adjustably carrying said holder at its opposite end, and a spring for forcing said separator or wiper and its holder toward the carrier with a yielding pressure, substantially as described.

10. The combination, with a rotary disk having a cambered or conical operating surface, a rotary feeding wheel, and a feeding plate, of a rotary carrier provided with a feeding surface adapted to engage with a check or other article and carry it forward, a coöperating separator or wiper, and a holder in and by which it may be held and adjusted, whereby checks or other articles supplied in packages or masses to the rotary disk, the rotary feed roll, and the feed plate are automatically fed forward to the carrier and separator or wiper, and the individual members thereof successively selected therefrom one at a time and started forward on their course through the machine, substantially as described.

11. The combination, with the printing or impression member of the printing mechanism normally held with the teeth of its operating gear disconnected from the teeth of its driving gear but capable of being brought into engagement with them to positively rotate such printing or impression member, of mechanism controlled in its movement by the presence or absence of a check or other article for respectively bringing the teeth of the operating gear of the printing member into, and for carrying it out of, engagement with the teeth of its driving gear, as the rotation or quiescence of the printing member is required, substantially as described.

12. The combination, with the rotary supporting member of the printing mechanism, a gear fixedly connected therewith, a print-

- ing or impression member, and a gear connected with this printing or impression member to rotate with it and having the teeth removed from a portion of its periphery, of means for normally holding this last mentioned gear stationary with the portion of its periphery from which the teeth are omitted opposite the gear connected and rotating with the supporting member, and mechanism controlled in its movements by the presence or absence of a check or other article for respectively bringing the teeth on the gear connected and moving with the printing or impression member into and carrying them out of engagement with the teeth on the gear connected and moving with the supporting member as the rotation or quiescence of the printing or impression member is required, substantially as described.
13. The combination, with the rotary supporting member of a printing mechanism, a gear F connected and moving therewith, and provided with recesses in the upper portion of its periphery, a printing or impression member, and a gear N connected and moving with such printing or impression member and constructed with teeth only throughout a portion of its periphery and with a stop segment throughout the remaining portion thereof for coöoperating with the gear F, of mechanism controlled in its movements by the presence or absence of a check or other article for respectively bringing the teeth on the gear N into and for carrying them out of engagement with the teeth on the gear F as the rotation or quiescence of the printing member is required, substantially as described.
14. The combination, with a rotary supporting member of a printing mechanism provided with feeding surfaces, a gear F connected and moving with such member and provided with recesses in the upper portion of its periphery, a printing or impression member, a gear N connecting and moving with such printing or impression member and constructed with teeth only throughout a portion of its periphery and with a stop segment throughout the remaining portions thereof for coöperation with the gear F, of an arm connected with said gear N and constructed with an outwardly and rearwardly curved surface, an abutment pivotally mounted upon the gear F and moving with it for coöoperating with the outwardly and rearwardly curved surface on said arm, a switch pivotally mounted upon a stationary part of the machine for coöoperating with the abutment to place it in a position to either engage with the arm connected with the gear N or to pass the same without engagement therewith as the switch is moved to one or the other limit of its movements, and mechanism con-

trolled in its operation by the presence or absence of a check or other article for adjusting the said switch to one or the other of its limits of movement as the rotation or quiescence of the printing or impression member is required, substantially as described.

15. The combination, with the gear F provided with recesses n^4 in the upper portion of its periphery, means by which it may be rotated, a gear N constructed with teeth only throughout a portion of its periphery and with a stop segment throughout the remaining portion thereof provided with an inwardly curved surface and outwardly extending tooth-like projections at its ends, and an arm fixedly connected with said gear N, of an abutment pivoted to the upper surface of the gear F for coöoperating with said arm, a switch pivotally mounted upon a stationary part of the machine for engaging with the operating end of the abutment to swing it either into a position to engage with said arm or into a position that will allow of its passing the same without engaging with it, and mechanism for moving this switch to one or the other of its limits of movement as the abutment is to be rendered operative or inoperative, substantially as described.

16. The combination, with the gear F provided with recesses n^4 in the upper portion of its periphery, means for imparting rotation thereto, a gear N constructed with teeth only throughout a portion of its periphery and with a stop segment throughout the remaining portion thereof that is provided with outwardly extending tooth-like portions at its ends, and an arm fixedly connected with said gear N, of a stop secured to the upper surface of the gear F in the path of movement of said arm, and mechanism for causing the rotation of the gear N when required, substantially as described.

17. The combination, with a gear F, means by which it may be rotated, and an abutment pivotally supported upon the upper surface of said gear and provided with an upwardly extending pin in its forward end, of a switch pivotally mounted above the abutment upon a stationary part of the machine and constructed with the opposite edges of its free end inclined inward toward each other for engagement with the upwardly extending pin on the abutment, and mechanism for swinging the switch to one or the other of its limits of movement to bring one or the other of its inclined edges into engagement with the pin on the abutment as the movement of such abutment is to be in one or the other direction, substantially as described.

18. The combination, with a rotary carrier provided with a feeding surface, a gripper carried by such carrier for coöoperating

- with said feeding surface, means for operating said gripper to cause it to grip and clamp a check or other article between it and the feeding surface at the point at which such check or other article is presented to it and release its hold upon it at the place where said check or other article is delivered, a radially movable detector mounted upon and carried by the carrier 10 and constructed with a down-turned inner end, a spring by which the detector is normally held pressed outward through the periphery of the carrier, selecting devices by which the successive checks or other articles 15 are selected one at a time and presented to such gripper, and a printing or impression member, of a switch pivotally mounted upon a stationary part of the machine, a curved guide wall with which the down-turned end of the detector engages, a stationary curved arm pivotally supported upon a stationary part of the machine outside the curved wall with which the down-turned end of the detector also engages, connecting devices 20 intermediately this pivoted curved arm and switch, and a spring for coöoperating with such pivoted curved arm, whereby the position of adjustment of the switch and the rotation or quiescence of the printing or impression 25 member is determined by the delivery or non-delivery of a check or other article beneath the gripper by the selecting and presenting devices, substantially as described.
19. The combination, with a rotary carrier 30 provided with a feeding surface, a gripper for coöoperating with such feeding surface, selecting devices by which the checks or other articles are successively selected one at a time from a mass and presented to the gripper and feeding surface, and mechanism by which the gripper is operated to clamp the check or other article to the feeding surface at the point where such check or other article is presented to it 35 by the selecting devices and to release its hold upon it at the place of its delivery, of a detector radially movable upon the carrier, and mechanism by which such detector is moved outwardly with a yielding pressure to detect the presence or absence of a check or other article upon the carrier and afterward protruded through the periphery of the carrier to detach the check or other article at the place of its delivery immediately after the gripper has released its hold upon it, substantially as described.
20. The combination, with a rotary carrier, a movable detector radially mounted
- thereon and constructed with a down-turned end, a gripper, mechanism by which such gripper is operated to clamp a check or other article and release its hold upon it at the required times, and a spring for normally pressing the detector in an outward direction, of stationary cams arranged in the path of such down-turned end for forcing the detector inward to the inner limit of movement and permitting of its outward protrusion through the periphery of the carrier by its coöoperating spring to release the check or other articles therefrom immediately after the gripper has released its hold upon it, substantially as described.
21. The combination, with the rotating carrier constructed with feeding surfaces, a gripper, a detector, and means for operating the gripper and detector, of a supporting plate, a pivoted stop plate located at the place at which the checks or other articles are delivered, and means for yieldingly holding the stop plate in its operative position, whereby such checks or other articles are supported on one of their edges as they successively arrive, with one against the other, and arrested in their forward movement after having been delivered, while yet, through the yielding action of the stop plate, any torn or crumpled check or other article may pass beyond, substantially as described.
22. The combination, with the printing member of the printing mechanism, the carrier, the shaft upon which the carrier is supported and carried, and the connecting devices intermediate such shaft and the printing member, of a clamping member fixedly secured to said shaft upon which the carrier may be rotated, a second clamping member between which and the first mentioned clamping member the carrier may be clamped, and means for forcing the two clamping members together, whereby upon releasing the clamping action of these clamping members, the carrier may be rotated around upon said shaft, and then firmly held in any adjusted position thereon by setting up or forcing such clamping members together, substantially as described.
- In testimony whereof I have hereunto set my hand in the presence of two witnesses this 31st day of March, 1909.
